UNITED STATES PATENT OFFICE.

LEROY M. E. CLAUSING, OF CHICAGO, ILLINOIS.

SYSTEM FOR GENERATING RADIOFREQUENCY CURRENTS.

Application filed August 16, 1923. Serial No. 657,746.

To all whom it may concern:

Be it known that I, LEROY M. E. CLAUSING, a citizen of the United States, residing at Chicago, in the county of Cook, State of Illinois, have made new and useful Improvements in Systems for Generating Radiofrequency Currents, of which the following is a specification.

My invention relates generally to the generation of high frequency electrical currents, and more particularly to the generation of such currents for radio transmission in those types of generators employing thermionic vacuum tubes.

One common method of generating powerful high frequency currents is that of employing a relatively low power vacuum tube to generate the oscillations, and impressing these oscillations upon one or more relatively high power vacuum tubes to amplify the oscillations. For instance a 50 watt vacuum tube may generate the oscillations and impress them on a pair of 250 watt vacuum tubes for amplification before utilizing the oscillations in the transmitting circuits. Such a system is commonly termed a "master oscillator-power amplifier" transmitter.

In the figure, VT_1 and VT_2 , diagrammatically represent two three-electrode thermionic vacuum tubes employed as power amplifiers for the master oscillator vacuum tube VT_3 . The plate circuits of the tubes VT_1 and VT_2 are supplied with energy from an alternating current source S through the transformer T and secondary S_1 . The secondary S_1 is tapped at its middle point and the lead from this tap is common to the filaments of both tubes VT_1 and VT_2 . The opposite terminals of secondary S_1 lead to the plates of these tubes. This arrangement provides for each tube alternately rectifying opposite half cycles of the alternating current plate supply. The secondary S_2 of the transformer provides for a low voltage heating current for the filaments of the tubes VT_1 and VT_2 , the resistances R_1 and R_2 providing a definite control over this heating current.

Both rectified halves of the source S are applied to the plate circuit of the vacuum tube VT_3 through the auto transformer X , so that the vacuum tubes VT_1 and VT_2 , in addition to performing the dual function of power amplification and self-rectification of the alternating current plate supply for their

own use, perform a third function of rectifying an alternating current source for use on the plate of the master oscillator tube. The secondary S_3 of the transformer T supplies low voltage current to the filament of the tube VT_3 , the value of the current being controlled by the rheostat R_3 . The oscillations of the master oscillator are impressed upon the grids of the power amplifier tubes through connections containing the grid-leak and stopping-condenser combinations G_1 and G_2 .

The condensers C and C_1 provide bypasses for radiofrequency currents around the high frequency chokes S_1 and X .

The inductance L_5 couples with the inductance L_3 to form a feed back for producing oscillations between the plate and grid circuits of the tube VT_3 . The inductance L_4 couples with the inductance L_3 to impress the oscillations of the tube VT_3 upon the grids of the amplifier tubes VT_1 and VT_2 . The condenser C_4 in connection with the inductance L_3 permits of tuning the plate circuits of the oscillator tube.

A illustrates an antenna coupled to the system through the inductances L , L_1 , and L_2 , permitting the antenna to be excited with the oscillations from the power amplifier tubes. The antenna has the conventional earth connection E . The condenser C_3 , short circuited by a keying arrangement K , provides for making signals in telegraphic communication. This means can without invention be substituted by means well known to the art for telephonic modulation of the oscillations.

It will be seen that I have provided a system for producing high frequency electrical oscillations employing vacuum tubes without the use of special generators in the plate circuits of the tubes and also have avoided the use of separate rectifying devices by arranging for the power amplifier tubes to simultaneously perform three functions.

Having described my invention, I claim:

1. A system for generating high power high frequency electrical currents comprising a source of low frequency alternating currents, means for impressing said low frequency currents upon a vacuum tube with which are associated self oscillation producing circuits, means for impressing said low frequency currents upon a pair of vacuum tubes with which rectifying and amplifying circuits are

associated, means associated with the said pair of vacuum tubes for impressing the said rectified currents upon the circuits of the first mentioned vacuum tube and means for impressing the oscillations in the circuits of said tube on the circuits of the said pair of vacuum tubes.

2. A system for generating high power high frequency electrical currents comprising a source of low frequency alternating currents, means for impressing said currents upon the plate-filament and filament circuits of a vacuum tube with which are associated self oscillation producing circuits, means for impressing said low frequency currents upon a pair of vacuum tubes, means associated with said pair of vacuum tubes for the simultaneous rectification of said low frequency currents and amplification of oscillations produced in the first mentioned vacuum tube.

3. A system for generating and radiating high power radio signals comprising a source

of low frequency alternating currents, means for impressing said currents upon a vacuum tube with which are associated self oscillation producing circuits, means for impressing said low frequency currents upon a pair of vacuum tubes with which rectifying and amplifying circuits are associated, means associated with said pair of vacuum tubes for impressing the said rectified currents upon the first mentioned vacuum tube, means associated with first mentioned vacuum tube for impressing the oscillations in a circuit of said vacuum tube on the amplifying circuits of the said pair of vacuum tubes, means associated with the last mentioned means for creating variations in the oscillations of the first mentioned tube to correspond to signals, and means associated with the said pair of vacuum tubes for impressing the varied amplified oscillations in the circuits of said tubes upon a radiating system.

LEROY M. E. CLAUSING.
